UNITED STATES PATENT OFFICE.

BENURI O. SWEUM, OF HAMAR, NORTH DAKOTA.

CARPENTER'S SQUARE.

1,061,423.

Specification of Letters Patent. Patented May 13, 1913.

Application filed July 23, 1910. Serial No. 573,468.

To all whom it may concern:

Be it known that I, BENURI O. SWEUM, a subject of the King of Great Britain, residing at Hamar, in the county of Eddy, 5 State of North Dakota, have invented certain new and useful Improvements in Carpenters' Squares; and I do hereby declare the following to be a full, clear, and exact description of the invention, such as will 10 enable others skilled in the art to which it appertains to make and use the same.

This invention relates to carpenters' squares.

The object of the invention resides in the 15 construction of a carpenter's square in which the tongue and blade are so arranged and connected that they may be moved at will so as to be disposed at different angles to each other.

20 A further object of the invention resides in providing means for effecting the angular adjustment of the blade and tongue and for positively maintaining said adjustment without providing any independent means 25 for locking the blade and tongue against relative movement.

A still further object of the invention is 30 the provision of means for indicating the various angular adjustments of the blade and tongue as they are attained.

Another object of the invention resides in forming a number of the elements integral to provide an efficient device consisting of few parts and which can be manufactured 35 at a minimum cost.

With the above and other objects in view the invention consists in the details of construction and in the arrangement and combination of parts as will be hereinafter 40 more fully described and particularly pointed out in the appended claim.

In describing the invention in detail reference will be had to the accompanying drawings wherein like characters of reference 45 denote corresponding parts in the several views; and in which,

Figure 1 is a plan view of a fragment of a carpenter's square constructed in accordance with the invention, the tongue and 50 blade being shown in the usual angular relation of 90°; Fig. 2, a view similar to Fig. 1 with the tongue and blade disposed at an angle of 120°; Fig. 3, a section on the line 3—3 of Fig. 1; and, Fig. 4, a section on the 55 line 4—4 of Fig. 1.

Referring to the drawings, A indicates

the blade of the square and B the tongue which is pivotally connected with the outer end of the blade A as at 10. The meeting ends of the blade A and the tongue B are 60 beveled at an angle of 45 degrees to provide faces which are adapted to lie against each other when the tongue B is in its normally closed position or at right angles to the blade A.

65 Formed in the blade A and opening through the beveled end thereof adjacent the beveled end of the tongue B is an elongated arcuate recess or bore 11 having the pivot 10 as its center. An arcuate groove 70 12 is formed in one side of the blade A and opens through the beveled end of said blade adjacent the beveled end of the tongue B; said groove 12 being disposed between the recess or bore 11 and the pivot 10, said pivot 75 constituting the center about which the groove extends. Projecting from the beveled end of the tongue B adjacent the beveled end of the blade A and mounted for travel in the groove 12 during the movement of the tongue B on the pivot 10 is an arcuate guide 13, while an arcuate screw 80 thread rod or member 14 also projects from the beveled end of the tongue B and is mounted for travel in the recess 11 during 85 the movement of the tongue upon the pivot 10. Extending transversely through the blade A adjacent the beveled end thereof and intersecting the recess or bore 11 is an aperture 15 and disposed in said aperture is 90 a thumb nut 16 through which the screw threaded member 14 is adapted to travel.

95 From this construction it will be apparent that by rotating the thumb nut 16 in one direction the angle of distribution of the blade and tongue may be increased beyond 90° while the rotation of said nut in the opposite direction will tend to return the tongue and blade to an angular disposition of 90°.

100 The face of the blade A is suitably sealed adjacent the outer side of the guide 13 for the purpose of indicating the increased angular adjustment of the tongue B, the coincidence of the end of the guide with the desired scale indicating the adjustment.

What is claimed is:—

110 In a carpenter's square, a blade having a beveled end, a tongue having a beveled end hinged to the beveled end of the blade, the beveled ends of the tongue and blade being fitted snugly together when the blade and

tongue are at right angles to each other, said tongue having an arcuate adjusting screw thereon, said blade having a recess which entirely incloses and protects the free end of the arcuate adjusting screw, said recess being formed with an enlarged portion, a nut seated in the enlarged portion and engaging the adjusting screw in coöperative relation for forcing the beveled ends to swing on their hinged connection, the nut being cylindrical and knurled and of a less diameter

than the thickness of the blade, so that it cannot contact with a plane solid surface, but may be easily rotated by contact with a thumb or finger of an operator. 15

In testimony whereof, I affix my signature, in presence of two witnesses.

BENURI O. SWEUM.
